W. C. WITHERSPOON,
EXTENSIBLE INCANDESCENT LAMP,
APPLICATION FILED JULY 9, 1917.

1,276,849.

Patented Aug. 27, 1918.

UNITED STATES PATENT OFFICE.

WILLIAM C. WITHERSPOON, OF BAKERSFIELD, CALIFORNIA.

EXTENSIBLE INCANDESCENT LAMP.

Specification of Letters Patent.

Patented Aug. 27, 1918.

1,276,849.

Application filed July 9, 1917. Serial No. 179,451.

To all whom it may concern:

Be it known that I, WILLIAM C. WITHERSPOON, citizen of the United States, residing at Bakersfield, in the county of Kern and State of California, have invented certain new and useful Improvements in Extensible Incandescent Lamps, of which the following is a specification.

My invention relates to improvements in electric lighting devices, and it consists of the constructions, combinations and arrangements herein described and claimed.

An object of my invention is to provide an extensible electric light arranged on one of the arms of an ordinary chandelier, a suitable spring actuated current wire bobbin being mounted on the chandelier and having suitable pawl and ratchet devices, so engaged as to permit the extension of one 20 of the incandescent bulbs to effect illumination of a remote point.

Another object of the invention is to provide a ball and socket fastener for receiving the extensible electric light whereby the 25 electric light may be replaced and held in its position on one of the chandelier arms when the electric light is not in use.

Other objects and advantages will appear from the following specification, reference 30 being had to the accompanying drawings, in which:

Figure 1 is a side elevation of a chandelier illustrating the application of my invention,

Fig. 2 is a vertical section of the bobbin box mounted on the chandelier which contains the spring actuated bobbin around which the extensible current wire is wound,

Fig. 3 is a detail section of the ball and 40 socket fastener,

Fig. 4 is an inverted section on the line 4-4 of Fig. 2, and

Fig. 5 is an enlarged fragmentary sectional view of a portion of the device, illustrating specifically the electrical connections with the conductor heads to be hereinafter referred to.

By reference to Figs. 1 and 2 of the drawings, it will be observed that a bobbin box 50 1 is mounted on the lower end of the standard 2 of a chandelier of any usual construction. A plurality of arms 3 radiate from the bobbin box 1 and are arranged to sup-

port the incandescent bulbs 4 at their ends. One of the radiating arms 3 is provided 55 with a bulbular enlargement 5 as shown in Fig. 3. A correspondingly shaped socket 6 formed at the top of a removable incandescent lamp 7 is adapted to slip over the bulbular enlargement 5 and be retained thereon. The socket 6 is flared to provide a throat-way for facilitating the attachment of the removable incandescent lamp 7 to the arm 3 of the chandelier. The socket 6 and the flared throat-way 8 are slotted as illustrated 60 in Fig. 1 to give the socket the required resiliency and permit its engagement over the enlargement 5.

Arranged within the box 1 is a bobbin 9 which includes the upper and lower flanges 70 10 and 11. The bobbin 9 is hollow as at 12 and is counter-bored as at 13 to admit a staff 14. The staff 14 is secured to the base of the bobbin box 1 as shown in Fig. 2.

The flange 10 of the bobbin 9 is recessed 75 as at 15 to receive the enlargement 16 of a bearing and supporting sleeve 17. The sleeve 17 has a flange 18 by means of which the sleeve 17 is securely wedged in the tubular standard 2 of the chandelier. The sleeve 80 17 is tubular as will be observed in Fig. 2 and receives the cord 19. The cord 19 may be tapped at any place above the flange 10 of the bobbin 9 to supply current to the incandescent lamp 4 of the arm 3. This cord 85 as well as the other cords hereinafter referred to, consists of the usual two wires insulated from each other and having a fabric covering, as illustrated in Fig. 3.

The cord 20 which supplies current to 90 the removable incandescent lamp 7 is not tapped directly to the current cord 19 as are the cords that supply the other incandescent lamp, for the obvious reason that this cord would soon twist off when the bobbin 95 9 turns first in one and then in the other direction. The cord 20 is held in a dielectric bushing 20' in the body of the bobbin 9 and has terminal ends 27.

The terminal ends 27 extend into the 100 counter-bore 13 and engage the conductor-heads 28 which are in electrical connection with the cord 19 and are supported beneath the bearing 16 by a dielectric bushing 29.

The conductor-heads 28 are of course 105 stationary and the terminal ends 27 bear

against the conductor-heads as the bobbin 9 turns. The cord 20 is therefore always alive when the snap-switch at the incandescent lamp is closed.

- 5 The bobbin 9 around which the cord 20 is wound, is actuated in one direction by a coiled spring 21 which occupies the hollow portion 12 of the bobbin. The coiled spring 21 is secured to the staff 14 at one end and 10 at the other end to the wall of the hollow portion 12. The latter point of attachment of the spring 21 may be bound adjacent to a bearing 22 secured to the bottom of the staff 14 in any suitable manner.
- 15 The bearing 22 has a flange 23 which bears against a counter-recess 24 in the lower flange 11 of the bobbin 9. It is of course desirable and necessary that the bobbin 9 rotate smoothly without rattling.
- 20 The flange 11 of the bobbin 9 has ratchet teeth 25 arranged on the upper surface of the periphery. A finger-operated pawl 26 engages the ratchet teeth and holds the bobbin 9 from rotating against the tension of 25 the spring 21. The pawl 26 has a finger-piece 26^a which is accessible from the outside of the casing 1.

The operation of the device is as follows. The manner of assembling the device may 30 be readily understood from Fig. 2, wherein it will be seen that the bobbin 9 is slipped into position on the bearing 16 in the casing 1. The bearing 22 is then adjusted in the proper position on the staff 14 which is carried by the lower part of the casing 1, so that the staff 14 extends into the counter-bore 13 and the bearing 22 engages the bobbin 9.

The spring 21 is ordinarily under little 40 tension and is put under tension only when the lamp 7 is pulled away from the bulb 5 and the cord 20 is extended. When the lamp 7 is removed from the socket and the cord 20 is pulled on, the cord 20 will unwind from 45 the bobbin 9 which will then rotate and tension the spring 21. At the same time, the pawl 26 will ride over the ratchet teeth 25 and finally when the pull on the cord ceases, the bobbin 9 will be held in position by the 50 pawl 26.

Should it now be desired to restore the lamp 7 to its place on the socket 5, the extended cord 20 is then grasped about in the middle with one hand while holding the 55 lamp with the same hand and reaching up to press down on the finger-piece 26^a with one of the fingers of the other hand. This releases the ratchet teeth 25 from the pawl 26 when the spring which is now under tension, 60 will turn the bobbin 9 in a counter direction and rewind the cord 20 thereon. Instead of using a pawl and ratchet device in connection with the bobbin 9, it may be found more desirable to use a ball-clutch. As an

incidental feature of the construction, it 65 should be observed that the corners of the various pipe brackets of the chandelier, are fully rounded so that the cord and more particularly the cord 20, may not bind when it is pulled out as above stated.

70 It should also be observed that the end of the staff 14 is supported at its upper end in the counter-bore 13. The staff 14 is of course fixed to the lower portion of the casing 1, but were it not for the support at the 75 counter-bore 13 for the end of the staff, the staff might become loosened with a bad effect on the bobbin 9.

75 While the construction and arrangement of the device as illustrated in the accompanying drawing is that of a generally preferred form, obviously modifications and changes therein may be made without departing from the spirit of the invention and the scope of the appended claims.

80 I claim:

85 1. In a device of the class described, the combination of a bobbin box, a shaft carried by said bobbin box, a bearing carried by said shaft at a point above the lower end 90 thereof, a sleeve projecting into the opposite end of said box, said sleeve having an enlargement upon its inner end, a bobbin having recesses in its ends, said bearing fitting within the lower recess and said enlargement fitting within the upper recess, thus 95 rotatably supporting the bobbin, and means for normally urging said bobbin to rotate in one direction.

100 2. In a device of the class described, the combination of a bobbin box, a shaft carried within said box, a bearing carried upon said shaft, a sleeve extending into the opposite end of said box and having a bearing upon its inner end, a bobbin having recesses in its 105 ends carried by said bearings, said bobbin having a counter-bore, a bushing carried by said sleeve and extending beyond the inner end thereof, a conductor carried by said bushing, conductor heads carried by said conductor, said conductor heads being within said counter-bore, a conductor or cord having their terminal ends extending into said counter-bore, said terminal ends engaging said conductor heads, means for urging 110 said bobbin to rotate in one direction and means for holding said bobbin against accidentally rotating.

115 3. In a device of the class described, the combination of a bobbin box, a shaft carried 120 within said box, a bearing carried upon said shaft, a sleeve extending into the opposite end of said box and having a bearing upon its inner end, a bobbin having recesses in its ends carried by said bearings, said bobbin 125 having a counter-bore, a bushing carried by said sleeve and extending beyond the inner end thereof, a conductor carried by said

bushing, conductor heads carried by said conductor, said conductor heads being within said counter-bore, a conductor having bare terminal ends extending into said counter-bore, and said terminal ends engaging said conductor heads.

In testimony whereof I affix my signature in presence of two witnesses.

WILLIAM C. WITHERSPOON.

Witnesses:

LOUIS V. BENNETT,
O. B. SMITH.
